UNITED STATES PATENT OFFICE

ROBERT F. FISHER, OF CLEVELAND, OHIO

CODE SIGNAL APPARATUS

Application filed January 13, 1930. Serial No. 420,401.

This invention relates to signal apparatus and more particularly to code signal apparatus adapted to assist in learning and in practicing telegraph codes.

Various devices have heretofore been proposed and used to assist in learning and practicing the sending and reception of telegraph and wireless signals. Among these may be noted buzzer coils which may be connected to a standard telegraph key to produce the regular buzzer signals in a set of ear-phones, spark or induction coils so connected up as to produce the same results, and various battery operated devices for causing audible signals in a set of head phones in accordance with the actuation of telegraph keys. All of the above types of apparatus, however, are necessarily rather complicated and it is among the objects of my invention to provide a simple apparatus for producing code signals which may be connected directly to a standard 110 volt A. C. power line.

Other objects of my invention are the provision of a code signal apparatus consisting of only two elements, viz. my improved key and a telephone receiver, and the provision of a self-contained key and resistance unit adapted to be connected directly to a 110 volt A. C. line and to a head-phone whereby danger of shock to the operator and burning out of the head-phones is eliminated.

The above and other objects of my invention will appear from the following description of a preferred form thereof, reference being had to the accompanying drawings, in which:

Fig. 1 is a plan view of my telegraph key with voltage regulator mounted on the same base.

Fig. 2 is a fragmentary section taken on line 2—2 of Fig. 1.

Fig. 3 is a section taken on line 3—3 of Fig. 1.

Fig. 4 is a sectional end view of my key and voltage regulator taken on line 4—4 of Fig. 1.

Fig. 5 is a detached side view of one of the resistance or condenser units adapted for use with my voltage controller.

Fig. 6 is an end view of the resistance or condenser unit shown in Fig. 5.

Fig. 7 is a wiring diagram of a code practice set with my improved telegraph key and resistance unit connected to a telephone receiver and to a 110 volt alternating current supply line.

Fig. 8 is a view similar to Fig. 7 but showing a resistance on one side of the A. C. line and a condenser on the other side.

Fig. 9 is a view similar to Figs. 7 and 8, but showing a resistance on one side only of the A. C. supply line.

In the preferred form of my apparatus illustrated in the drawings, the telegraph key and voltage control unit are both mounted on the baseboard 10. The key lever 11 is flexibly secured to the voltage regulator case 25 by means of a flat spring 12. This spring 12 is firmly held in position on the top of the case 25 by means of the bolts 27. A coil spring 13 rests on the base 10 below the lever 11 and is normally in compression to tend to push the lever upwardly. A thumb screw 14 and locking nut 15 are provided to permit adjustment of the tension spring 13 which tends to lift the lever 11. The contact member 16 is preferably riveted to the lever 11 and the co-acting contact point 17 is secured directly below the contact point 16.

The handle knob 19 is secured to the end of screw 20 which, as shown in Figure 3, has threaded engagement with the hole in the end of lever 11. The lock nut 21 is adapted to engage the underside of the lever 11 and lock the lever in any desired position on the screw 20. The screw 20 extends downwardly and passes through an aperture in the base 10, and is permanently fixed to the combined guide and stop member 22. This guide 22 is adapted to slide in the aperture in the base 10 and has a shoulder portion engaging the underside of the base 10 to limit the upward movement of the lever 11.

It will be clear that by the above construction when the locknut 21 is loosened and the knob 19 turned, the screw 20 will also turn and be moved relative to the lever 11 due to the threaded engagement therewith. Thus

by turning the knob 19 in the proper direction the lever 11 will be raised or lowered and the distance between the contact points 16 and 17 can be accurately adjusted.

The voltage regulator case 25 contains a resistance unit 24 and a condenser unit 23. The condenser unit 23 and resistance unit 24 are preferably made to be interchangeable in the regulator case 25 and are held in place by

10 grooves in the case, which grooves also contain spring contacts 29 and 31, which make the electrical connection from the 110 volt line terminals to the resistance unit on one end and from the opposite end of the resistance unit to the telegraph key terminal. Screws 30 hold the spring clip 29 in place in the housing 25 and also serve as binding screws to which the ends of the line current conducting cable may be connected.

20 As seen in Figure 2 the spring contact member 31 is of a different shape than the contact member 29. Its purpose, however, is the same, and it serves to connect one end of the condenser unit 23 to the flat spring 12 and through the lever 11 to the contact 16.

The phone cord binding posts are of standard form and are shown in the drawings as being made up of the attaching screws 32 and 33, post member 35 and thumb screws 36.

30 The upper binding post (Fig. 1) is of slightly different construction than the lower binding post in that the attaching screw 33 extends downwardly through the base 10 and is held in position by the nuts 34, while the attaching screw 32 of the lower binding post abuts against the under side of the regulator case 25 and is adapted to make electrical contact with and hold in position the contact spring 29.

40 The baseboard 10 may be held up out of contact with the surface on which it is supported by means of the rubber buttons 37. A strip of metal, preferably copper, or other

45 good electrical conductor, extends between the stud 33 of the phone binding posts and the lower contact point 17. This strip 39 is held in position against the bottom of the base 10 and in good electrical contact with

50 the binding post and the contact point 17 by means of nuts 18 and 34, respectively.

In Figs. 7, 8 and 9 I have shown several ways of connecting my key and voltage regulator unit to an alternating current line and a pair of head phones.

60 In the hook-up illustrated in Fig. 7 the resistance units 24 control the current which passes through the key contacts and the telephone receivers. The higher the resistance of the unit, the less current passes through the telegraph key contacts. As shown in the drawings and described above, these resistance units 24 are removable and can be changed to other units of higher or lower re-

sistance so as to regulate the strength of signals in the telephone receivers.

In the alternative hook-up illustrated in Fig. 8 a resistance 24 is connected in one side of the A. C. line and a condenser 23 on the 70 other side. This condenser has the same outside shape as the resistance unit to fit in the same groove in the regulator case 25.

In Fig. 9 a single resistance unit 24 is used on one side of the A. C. line. This hook-up will give satisfactory operation, but is not as desirable as the others illustrated as there is a certain amount of danger of shock to the operator on account of the unprotected side of the line leading to the telephone receivers.

While I have described the illustrated embodiment of my invention in some particularity, modifications and variations thereof may occur to those skilled in the art to which it pertains. For example, condensers similar to condenser 23 might be inserted on both sides of the A. C. supply line and it would be perfectly practicable to connect a number of sets of telephone receivers and keys in series so that a class or group could be instructed in code transmission and reception. In this latter case the keys not in use would necessarily be locked in the closed position to permit the apparatus to operate. I do not, 95 therefore, limit myself to the precise details shown and described, but claim as my invention all embodiments there coming within the scope of the appended claims.

I claim:

1. In a code signal practice device, a base member, a socket adapted to receive a current restricting device carried by said base, a pair of relatively movable contacts carried by said base, means connecting one side of said socket to one of said contacts, and means connected to the other of said contacts adapted to be connected to a receiver.

2. In a code signal practice device, a base member, a socket adapted to receive a current restricting device carried by said base, a lever movably mounted on said base, cooperating contact points on said base and said lever, means tending to separate said contacts, a handle on said lever, and means limiting the separation of said contacts associated with said handle in such a manner that adjustment thereof may be effected by movement of said handle.

3. In a code signal practice device, a base member, a socket adapted to receive a current restricting device carried by said base, a lever movably mounted on said base, co-operating contact points on said base and said lever, a 125 spring urging said lever away from said base, a handle having a stem threaded through said lever, a lock nut on said stem to secure the same in adjusted position, a sleeve carried by the end of said stem, said base hav-

ing an enclosed aperture extending there-through and slidably receiving said sleeve to guide said lever and limit the movement thereof away from said base.

5 In testimony whereof I hereunto affix my signature this 9th day of January, 1930.

ROBERT F. FISHER.
